UNITED STATES PATENT OFFICE.

MARCUS LAFAYETTE SAUNDERS, OF THOMAS COUNTY, GEORGIA.

DESIGN FOR A PLOW-HOE.

SPECIFICATION forming part of Design No. 16,345, dated October 20, 1885.

Application filed August 18, 1885. Serial No. 174,752. Term of patent 14 years.

To all whom it may concern:

Be it known that I, MARCUS LAFAYETTE SAUNDERS, of Twenty-third district, in the county of Thomas and State of Georgia, have 5 invented and produced a new and original Design for a Pulverizing Plow-Hoe, of which the following is a full, clear, and exact description.

Reference being had to the accompanying 10 drawings, forming part of this specification, Figure 1 is a plan view of my newly-designed pulverizing plow-hoe. Fig. 2 is a cross-section of the same, taken through the line x x , Fig. 1. Fig. 3 is a side elevation of the same; 15 and Fig. 4 is a sectional side elevation of the same, taken through the line y y , Fig. 1, these four views being deemed necessary to fully illustrate my design.

The leading feature of my design consists 20 in the rhomboidal-shaped plow-hoe having a flat angular cutting-edge, and being convexed transversely and concaved longitudinally.

A is the cutting-edge of the plow-hoe, which is angular, as shown in Fig. 1, and flat, as shown in Figs. 2, 3, and 4. The plow-hoe is convexed transversely, as shown in Figs. 2 and 3, and is concaved longitudinally, as shown in Figs. 3 and 4. 25

I claim—

The design for a pulverizing plow-hoe here- 30 in shown and described, the same consisting of a rhomboidal-shaped plow-hoe having a flat angular cutting-edge, and convexed transversely and concaved longitudinally, said flat cutting-edges upon both sides of the hoe being in the same horizontal plane. 35

MARCUS LAFAYETTE SAUNDERS.
